UNITED STATES PATENT OFFICE.

PATRICK JAMES NEILON, OF CONNERSVILLE, INDIANA.

AUTOMATIC SPRINKLER SYSTEM.

1,212,096.

Specification of Letters Patent.

Patented Jan. 9, 1917.

Application filed July 8, 1916. Serial No. 108,228.

To all whom it may concern:

Be it known that I, PATRICK J. NEILON, a subject of the King of England, residing at Connerville, in the county of Fayette 5 and State of Indiana, have invented certain new and useful Improvements in Automatic Sprinkler Systems, of which the following is a specification, reference being had to the accompanying drawings.

10 This invention relates to certain improvements in automatic sprinkler systems wherein a suitable alarm is provided to be operated whenever there is a continuous discharge of water through the system due to 15 the opening of one or more of the sprinkler heads.

It is another and more particular object 20 of the invention to provide in combination with two sprinkler systems and a single hydraulically operated alarm device there- 25 for, means automatically operating to prevent the passage of water from one system into the other when the former is in opera- 30 tion.

25 The above noted object is accomplished by means of a single double-acting check valve interposed between the pipe connec- 35 tions of the sprinkler systems and the alarm device and which normally grav- 40 itates to a position to close communication between one of the systems and said device, said valve after the operation of either system, permitting the water to drain back through the pipe connections into the return 45 chambers from which it is discharged 50 through suitable waste ports.

It is a further general object of the invention to provide a device for the purpose 55 above stated, which is exceedingly simple 40 and will not add materially to the cost of installation of such automatic sprinkling systems and may be advantageously em- 50 ployed either with "dry" or "wet" systems or a combination of the two.

45 With the above and other objects in view, my invention consists in the novel features 60 of construction, combination, and arrange- 55 ment of parts to be hereinafter more fully 65 described, claimed and illustrated in the accom- 70 panying drawing, in which,

Figure 1 is an elevation showing two 75 sprinkler systems of the type generally known as the Rockwood system illustrating 80 the pipe connections between the same and

the hydraulically operated alarm device 55 with my improved double-acting control valve arranged therein; Fig. 2 is an en- 60 larged vertical section of the check valve; and Fig. 3 is a similar view showing a slightly modified form of the valve. 60

In the accompanying drawing, for illus- 65 trative purposes only, I have shown my in- 70 vention as applied to the latest improved type of the Rockwood automatic fire sprin- 75 kler system, which generally corresponds in 80 all essential features to the apparatus shown and described in Patent #1,051,266, issued to George I. Rockwood, January 21st, 1913. It is to be clearly understood, however, that 85 my invention is not limited in its practical 90 application, to this particular sprinkler sys- 95 tem but may also be advantageously em- 100 ployed in various other systems of the "dry" or "wet" type known to the art.

As the sprinkler system *per se* constitutes 75 no part of the present invention, its detail 80 features will not be specifically described and a general reference to the system will suffice with the purposes of the present 85 specification. Referring then to the accom- 90 panying drawing, 5 designates the sprinkler 95 supply pipe which is fed from a pipe 6 leading to a source of water supply under pres- 100 sure. Between these pipes 5 and 6, a suit- 105 able casing or housing 7 is interposed in 110 which any approved type of valve is con- 115 tained to normally cut off communication 120 between the feed pipe and the sprinkler 125 pipe 5. A suitable pressure gage indicated 130 at 8, is preferably provided whereby the 135 water pressure passing through the valve 140 chamber may be ascertained.

9 designates the return chamber and 10 a 145 pipe connection between the lower end of 150 this chamber and the by-pass which is nor- 155 mally closed by the cut-off valve in the cas- 160 ing 7. A waste pipe 11 is connected to the 165 bottom of the chamber 9 and within said 170 chamber a suitable valve mechanism is pro- 175 vided to close the waste pipe 11 when water 180 under pressure is admitted to said chamber. 185

12 designates a hydraulically operated 190 alarm device which may be similar to that 195 disclosed in the patent above referred to and 200 consists in a suitably constructed water 205 wheel, to the shaft of which a hammer 13 is 210 fixed for engagement with a bell 14. A pipe 215 220 is connected to the upper end of each of

the return chambers 9 and is connected to a suitable casing 16 in which a diaphragm or other movable means is arranged to be actuated under the pressure of the water and close an electric circuit whereby the alarm bell 17 is operated. To each of the pipes 15 a horizontally disposed pipe 18 is connected and these pipes are joined to a vertical pipe 19 by means of a T-shaped coupling 20. The pipe 19 is connected to the casing of the alarm device 12 to discharge water upon the vanes or buckets of the wheel mounted therein. An internal annular shoulder or seat 21 is formed in the coupling member 20 below the laterally projecting nipple thereof and at the inner end of this nipple a second annular shoulder or seat 22 is formed.

23 indicates a gravity check valve which is pivoted or fulcrumed as at 24 within the coupling 20 and at the juncture or contiguous portions of the two valve seats 21 and 22. Normally, the valve plate 23 is engaged upon the seat 21 and closes communication between the sprinkler system at the left of the drawing and the one on the right, said latter system being in open communication through the pipes 18 and 19 with the alarm device 12.

Assuming that one of the sprinkler heads 30 of the system at the left of the drawing is broken or destroyed, the pressure of water through the pipe 6 will open the valve in the chamber 7 and the main volume of water will pass into the pipe 5. Some of the water will flow through the bypass of the pipe 10 and the return chamber 9. This chamber will rapidly fill and the water will rise through the pipe 15 and actuate the circuit closer to ring the bell 17. The water will 40 also pass through the pipe 18 and force the check valve 23 upwardly into engagement upon the seat 22 and thus rise through the pipe 19 and actuate the hydraulically operated alarm device 12. It will thus be seen that the valve 23 effectually closes communication between the pipe 19 and the right-hand sprinkler system so that there will be no passage of the water from the system which is in operation to the other of the 50 sprinkler systems. After the pressure of water decreases, the valve plate 23 will return to its normal position upon the seat 21 and the water will drain back through the pipes 19 and 18 and into the return chamber of the right-hand sprinkler system to be discharged through the waste pipe 11 thereof, while the water remaining in the other pipe 18 is drained in a similar manner through the return chamber of the left-hand sprinkler system. It will be understood, of course, that when the right-hand sprinkler system is in operation, the valve 23 remains in its normal position upon the seat 21. Thus it will be seen that by the 60 provision of my improved double-acting

check valve, only one hydraulically operated alarm device is necessary for two sprinkler systems, and the passage of the water into the pipe 19 from either system is automatically controlled and back pressure into the 70 pipe connections of the inoperative system precluded.

25 indicates the waste pipe connected to the valve casing 7 of each sprinkler system and 26 a suitable hand operated valve whereby communication between the pipe 25 and the valve casing may be opened and the water drained from said casing and the sprinkler pipe 5.

From the foregoing description taken in connection with the accompanying drawing, it is believed that the construction, manner of operation and several advantages of my improved controlling valve for the alarm operating means may be clearly and fully understood. I am aware of the fact that check valves similar to that above disclosed have been commonly used for various purposes but I am not advised that the particular application of such valve in combination with two sprinkler systems for the purpose above referred to has been previously employed in the art. The advantage incident to such use of the double-acting check valve is believed to be clearly manifest. The device itself is 95 exceedingly simple, may be readily installed and applied at small cost and without necessitating any material alterations whatever in the construction or arrangement of the several parts of the system. It is, of course, apparent that the present invention is not confined to use in connection with alarm devices of the type herein disclosed, but any other desirable means for producing an audible alarm in the operation of the 100 sprinkler systems may be substituted therefor.

The invention itself is also susceptible of minor modifications in the form and construction of the several features and I, therefore, reserve the privilege of adopting all such legitimate changes as may be fairly embodied within the spirit and scope of the invention as claimed.

In Fig. 3 of the drawing I have shown a 115 slightly modified form of the valve wherein the valve casing is provided with two diverging branches 27 adapted to be coupled to the pipes 18 of the respective sprinkler systems. The valve seats 27' are obliquely inclined and the valve plate 23' is pivotally mounted between said valve seats, as at 24'. A coupling head 28 is threaded upon the valve casing and has an interiorly threaded extension for connecting to the pipe 19. 120 This form of the valve operates in a similar manner to that above described to close the pipe 18 of one sprinkler system when the other is in operation, the valve plate 23', however, being obliquely disposed when in 130

its closed position so that it will move somewhat more quickly and under a less pressure from one position to the other, than is the case in the operation of the valve first described.

Having thus described this invention, what is claimed is:—

1. The combination with two automatic sprinkler systems and a single, hydraulically-operated alarm device, of a pipe extending from each sprinkler system, a supply pipe for the alarm device, a T-shaped coupling member connecting said pipes and having internal valve seats extending at right angles with respect to each other, a valve plate pivotally mounted within the coupling member at the juncture of the valve seats to engage upon the respective seats and prevent the passage of water from one sprinkler system into the other when the former is in operation, said valve, when in either position, being disposed in parallel relation to the direction of flow of the water from the operat-

ing sprinkler system into the supply pipe of the alarm device.

2. The combination with two automatic sprinkler systems and a single hydraulically-operated alarm device, of a pipe extending from each sprinkler system, a common pipe connection between the first named pipes and the alarm device, and a double-acting check valve interposed between said pipes at the juncture thereof to prevent the passage of water from one system into the other, when the former is in operation, said valve being held by the water pressure against movement to maintain open communication between the operating sprinkler system and the alarm device.

In testimony whereof I hereunto affix my signature in the presence of two witnesses.

PATRICK JAMES NEILON.
